UNITED STATES PATENT OFFICE.

JOHN R. ROHN, OF PITTSBURGH, PENNSYLVANIA, ASSIGNOR TO FEDERAL TOY PISTOL COMPANY, OF HOMESTEAD, PENNSYLVANIA, A CORPORATION OF PENNSYLVANIA.

TOY PISTOL.

1,144,791.

Specification of Letters Patent. Patented June 29, 1915.

Application filed October 22, 1914. Serial No. 868,045.

To all whom it may concern:

Be it known that I, JOHN R. ROHN, a citizen of the United States, and resident of Pittsburgh, in the county of Allegheny and 5 State of Pennsylvania, have invented certain new and useful Improvements in Toy Pistols, of which the following is a specification.

This invention relates to certain improvements in toy pistols of the general construction illustrated in patent to W. R. Atkinson, 10 No. 1,061,257, May 13, 1913.

One object herein is to render more effective the spring-opposed and spring-im- 15 pelled movements of the trigger and ham- mer by providing each with a separate spring arranged or positioned in such manner as not to retard true pivotal movements of the parts. This is best accomplished by 20 providing springs of coil form which embrace the trigger and hammer pivots, preventing the moving parts from so tipping or canting as to scrape or grind against the casing and thereby retard the movements of 25 said parts. Toys of this character are of comparatively rough and loose construction, and the scraping or binding of the working parts, due to canting or tilting under dis- 30 torting spring action, retards their operation. Accurate application of the spring force is also desirable in order to minimize movement obstruction resulting from rust and corrosion.

A further purpose is to afford the trigger 35 limited movement independently of the hammer before raising or cocking the latter, whereby the initial portion of the backward movement of the trigger is in the main op- posed only by the spring against which the 40 trigger acts, the resistance offered by the hammer not being encountered until after the trigger has had an appreciable start with the result that the load is taken up gradually and the mechanism is thereby caused to op- 45 erate with greater ease than though the entire load were encountered at the inception of the trigger movement.

A further purpose is to improve the construction of the pistol frame whereby con- 50 venient access may be had to its interior for inserting the cap strip roll, also for initially adjusting the strip to the feeding and firing mechanisms.

In the accompanying drawings, Figure 1

is an elevation of the internal mechanism of 55 a toy pistol embodying the invention, a portion of the casing being removed and the parts shown in normal position. Fig. 2 is a similar view with the hammer cocked and just before it is released. Fig. 3 is a view in 60 detail of the trigger and associated parts, and Fig. 4 is a similar view of the hammer. Fig. 5 is a cross-section taken on line 5—5 of Fig. 1. Figs. 6 and 7 are side elevations of the improved pistol, in Fig. 6 all of the 65 parts being shown in normal position, and in Fig. 7 the gate-like portion of the frame being shown open as when inserting the strip roll, the feeding and firing mechanisms being retracted for initially passing the strip 70 upwardly over the feeding and firing abutment. Fig. 8 is a cross-section taken on line 8—8 of Fig. 6.

Referring to the drawings, 2 designates the main portion of the pistol frame which 75 forms one-half of the grip or handle 3 and barrel 4, the portion of the frame removed from the disclosures of Figs. 1 and 2 completing the grip and barrel outlines, as in Fig. 6, and serving to inclose the mechanism. 80 At the rear of barrel 4 is the magazine cham- ber 5 for a percussion strip roll 6, which is adapted to pass upwardly over the upright guide or abutment 7, against the upper por- 85 tion of which the percussion spots of the strip are adapted to be fired by hammer 8.

The hammer is mounted between the upper portions of the sectional frame on stud 9 which projects from frame-part 2. The body portion of the hammer is formed on 90 its face adjacent part 2 with the open-end depression 10, and fitting in the latter and embracing stud 9 is the coiled spring 11. One extremity of the spring bears against the top wall of depression 10, and the other 95 and longer extremity 11' projects outwardly through the open end of the depression and engages the anchoring stud 12 on frame part 2.

The trigger 13 is mounted on the pivot- 100 forming screw 14 secured to frame part 2, with the coiled spring 15 embracing the screw and with one extremity of the spring engaging the frame and the other extremity a shoulder 13' of the trigger, thereby hold- 105 ing the latter normally in a forward position. An arm 16 projecting rearwardly from the trigger has pivoted to one side

thereof the strip-feeding pawl 17 and at its opposite side the sear 18, the pawl and sear being preferably formed with apertures to receive the projecting trunnions 19 on arm 16. Pawl 17 presses the percussion strip against abutment 7, forcing it upwardly step by step as the trigger is operated for presenting fresh portions to the hammer-striking upper portion of the abutment.

10 The upper extremity of sear 18 normally engages the guiding surface 20 of the inner portion of the hammer, said surface terminating in shoulder 21 which is adapted to be engaged by the sear for lifting and reTRACTING the hammer, as will be understood. The pawl and sear are held normally separated with the former pressing against abutment 7 and with the extremity of the sear in engagement with surface 20, the parts 20 being so held by the interposed spring 22 in much the same manner as the Atkinson patent above referred to. Normally, sear 18 engages surface 20 at a point slightly beneath shoulder 21, as in Fig. 1, thereby 25 affording the sear limited upward movement relatively to the hammer before the sear and shoulder are engaged for the hammer-raising or cocking movement. By this means the trigger is afforded slight initial 30 movement independently of the hammer, the resistance of the latter not being encountered until shoulder 21 is engaged by the extremity of the sear so that the trigger-pulling action is accomplished more easily 35 than though the entire resistance were encountered at the inception of the backward or firing movement of the trigger. The trigger having been pulled and the hammer raised, as in Fig. 2, the sear slips from shoulder 21, whereupon the hammer is thrown forward by spring 11 against the upper or firing portion of abutment 7. Upon releasing the trigger it and pawl 17 and sear 18 are restored by spring 15 to normal 40 position and in readiness to repeat the operation.

In order to conveniently insert a fresh strip-roll 6 and apply the strip initially to abutment 7, a portion of the front side frame 50 is in the form of a gate 23 which is hinged at 24 between the sectional barrel parts 4, the hinge-carrying extremity of the gate being in the form of a cam head 25 which is engaged by the flat spring 26, the pressure 55 of the latter operating to hold the gate closed as in Fig. 1, and when the gate is turned down into open position, as in Fig. 7, the spring then retains it in that position. The main portion of gate 23 closes the roll 60 magazine or chamber 5 and also incloses the upper portion of the trigger mechanism, and an extension 23' of the gate closes one side of the space in which the strip-feeding mechanism as well as abutment 7 are located.

65 When a fresh roll is to be inserted the gate

is turned down from the position shown in Fig. 6 to that of Fig. 7, thereby so opening and exposing the roll chamber and the space through which the strip feeds that the latter may be readily applied. After the roll is 70 slipped onto its spindle 6', the strip is passed upward over abutment 7, the operator reTRACTING the hammer and also the feeding pawl 17, as in Fig. 7, thereby leaving a clear space for the upward passage of the strip 75 over abutment 7. With the strip thus started, it will be fed automatically by the pawl until the entire roll has been used. With a gate of the form shown, the interior of the pistol is readily accessible for inserting the 80 roll and before passing the strip into operative relation with the feeding and firing parts. When the gate is closed the parts are as completely inclosed as though the gate were an immovable part of the side frame. 85

With the spring for the hammer arranged as shown, the latter is caused to have a true pivotal movement on stud 9 without tilting or canting, and hence without so scraping or grinding on the casing sides as to retard the 90 operation. And substantially the same condition is true of the pivotal action of trigger 13, spring 15 holding it true and imparting a concentric rather than a distorting resistance. 95

I claim:—

1. In a toy pistol, the combination of a frame having separable sides spaced apart and with the space open at the top, a hammer fitting and movable through the 100 open upper end of said space and held against lateral play by the frame sides, the hammer formed with a pivot passage and with a spring recess in one side, the open side of the recess closed by one of 105 the frame sides and with the recess open through the edge of the hammer, a transverse pivot stud projecting from the recess-closing face of the frame sides and across said recess and into the pivot passage 110 of the hammer, a spring within the hammer recess and coiled about said stud with one extremity of the spring in engagement with the recess wall, an abutment in the frame for the other extremity of the spring, and 115 hammer actuating means.

2. In a toy pistol, the combination of a frame containing a strip-roll magazine, strip feeding and firing mechanisms inclosed within the frame, said mechanisms 120 including an abutment extending downwardly from the top of the frame, the frame being open at one side to expose the magazine and also open downwardly from its top to expose the entire length of the abutment, 125 and a hinged gate for closing the open side of the frame, the gate including an upward extension for closing the space extending to the top of said abutment.

3. In a toy pistol, the combination of a 130

frame containing a strip-roll magazine, strip feeding and firing mechanisms within the frame and including an abutment over which the strip passes, the frame being open 5 at one side to expose the abutment and the magazine, a gate adapted to close the frame opening, the gate formed with a cam head, a hinge mounting for the head within the

frame, and a spring coöperating with the head for normally holding the gate closed. 10
In testimony whereof I affix my signature in presence of two witnesses.

JOHN R. ROHN.
